Inventor:

J. PABST.

UNITED STATES PATENT OFFICE.

JOSEF PABST, OF ZURICH, SWITZERLAND.

SAFETY-HOLDER FOR NECKTIES.

1,394,441.

Specification of Letters Patent. Patented Oct. 18, 1921.

Application filed February 24, 1920. Serial No. 360,641.

To all whom it may concern:

Be it known that I, JOSEF PABST, a citizen of the Republic of Switzerland, residing at Zurich, in the Canton of Zurich, Switzerland, have invented a Safety-Holder for Neckties, of which the following is a specification.

Holders for neckties, in combination with pins, are already in use. These holders have all for their object to safeguard the position of the necktie in relation to the collar stud or to attach it to the same, whereby one or more pins are made to penetrate the tie.

This invention is intended for another purpose, namely to preserve the form of the neckties, particularly those of the kind which are self-adjusted, that is to say those shaped and tied by hand. The necktie holders hitherto used, even those employing pins, are not adapted to serve the same end, inasmuch as the position and arrangement of the pins in relation to the holder are not suitable. In order to fulfil this condition at least one pin, that is one rigidly secured to the holder needs to be so disposed that when pressed from behind into the finished knot of the tie, it penetrates the binding part or slip and the loop of the self-adjustable tie. The position of these parts which are slideable within each other is thereby rendered secure. Apart from the single pin described, other pins may be employed for the same or other purposes. It is also clear that this safety-holder cannot be compared with clasps or other fastenings which are essentially designed for the attachment to or suspension from the collar stud of neckties of the finished type, that is of the kind in which the parts are sewn together.

In order that the invention may be clearly understood reference is made to the accompanying drawings, in which:

Figure 1 shows a side view of a safety-holder according to a first construction;

Fig. 2 shows a rear view thereof and as applied to a tie of which the binding of the parts has been effected from right to left;

Fig. 3 shows the same as applied to a tie where the parts have been adjusted and bound from left to right;

Fig. 4 shows a section through the knot of the tie with the holder in position;

Figs. 5 to 12 show various modifications of the safety-holder, each in front elevation;

Fig. 13 is a side elevation of a modification;

Fig. 14 represents a further modification in front elevation, and

Fig. 15 shows another side view of the same.

Fig. 16 is a front elevation of a last modification.

Similar parts are designated by like references to all the views.

Referring to the first construction, Figs. 1 to 4, 1 is a plate of metal or other suitable material having two integral members which are at an angle to each other and which are designated by *a* and *b* respectively. The upper portion of this plate is grooved or cut out at 2 so as to allow the cut out part to be brought up and pressed against the collar stud. The member *b* has four pins 3, 4, 5 and 6 rigidly attached thereto, at right angles, and of these pins those designated by 3 and 4 lie symmetrically on one side of a longitudinal center line *x*—*x* while the other pins 5 and 6 are disposed on the opposite side of the said center line. All the pins are situated below the point of attachment 2. The pins 3 and 4 are also symmetrically arranged in relation to the pins 5 and 6, each pair of pins being mounted on lines *y*—*y* running obliquely to the line *x*—*x*.

The manner of employment of the device described is as follows. Subsequent to the binding and tying of the knot and its adjustment against the collar, the tie thus adjusted is slightly lifted from the shirt front whereby the thumb and index finger of the user's left hand are made to press on the tie below the knot so that the slip 9 is prevented from being displaced and the tie consequently loosened. The holder is thereupon slid underneath the tie and made to engage the collar stud by means of the grooved part 2. The tie and holder are then pressed against each other whereby the pins are caused to penetrate the tie. In the Figs. 2,

3 and 4 the binding part or slip 9, which in the binding process has been also folded, represents one end of the self-adjusting tie, while 10 designates the first of a double loop within which the said slip, when not se-

cured, is adapted easily to slide, that is the tie slides downward. 11 is the second and outer portion of the double loop from which the other end of the tie freely suspends, and 5 12 is the cover part of the loop. In a tie of this kind and adjusted from right to left, the pins 5 and 6, as shown in Figs. 2 and 3, owing to the number of the pins and the disposition thereof penetrate the slip 9 the said 10 pins, as is clear from Fig. 4, also penetrating at least the inner portion 11 of the double loop so that these parts are secured together without, however, projecting through the cover part 12. A displacement of the slip 9 15 in the loop is therefore prevented. The pins 3 and 4 assist hereby in safeguarding more amply the position of the knot and the shape of the loop. In a tie bound or adjusted from left to right, Fig. 3, it is the pins 3 and 4 20 which connect the slip with the loop, and it is thus possible to apply this particular construction of the holder for both ways of adjustment or binding. Since the holder safeguards the form and position of the self- 25 adjusting tie, the employment of a clamp mostly used in order to secure the slip or both ends of the tie to the shirt front, without, however preventing a loosening of the knot of the tie, is obviated.

30 According to the modification illustrated in Fig. 5 the plate 1 is provided with a hole 7 through which the collar stud is adapted to be inserted if this mode of attachment, owing to the shape of the collar, is more convenient. Provision is hereby made, apart from the pins 3 and 5, of a third pin 13 which is mounted near the bottom and in the middle of the plate. This modified construction is likewise adapted for each mode 35 of binding the tie.

40 In the modification, Fig. 6, the pins 5 and 13 only are provided, it being understood that the pin 5 could also be replaced by the pin 3 on the opposite side.

45 In the modified construction, Fig. 7, provision is made of the pins 5 and 3, the pin 13 being entirely omitted.

The modification according to Fig. 8 shows the upper pins 5 and 3 and a lower pin 14 which may be mounted on the left side of the center line of the plate, as shown, or on the opposite side thereof.

In the next modification, Fig. 9, there is only the pin 13, arranged near the bottom 50 end of the plate 1 and in the center line thereof.

According to a further modification, Fig. 10, provision is made of the pin 3 only which, however, could be replaced by the pin 5 mounted on the opposite side. In another modification, Fig. 11, the plate is fitted with a single pin 14 mounted near the bottom of said plate and on one side of its center line. Instead of being arranged on the left side 65 as shown, it could of course also be fixed on

the opposite side, or, as illustrated in the modification, Fig. 12, two pins 14 and 15 could be provided these pins being near the bottom of the plate and symmetrically disposed in relation to each other and the center line. 70

In the further modification, Fig. 13, the pins 3' and 4' in this case being undulated in order to afford a better grip of the material. 75

In another modified construction, Figs. 14 and 15, there are two pins 13 and 16, one arranged above the other and both in the center line.

The last modification shows the plate 1 80 substituted by a wire frame 17 which at the upper end is curved inwardly so as to form the means for attachment to the collar stud. Pins 3, 5, and 13 are fixed to this wire frame in any convenient manner. In all these different forms of construction at least one pin is so mounted and arranged that it is adapted to penetrate the binding part or slip and the loop of the self-adjusting tie, thereby pinning these parts together. 85

Having now fully described my said invention what I claim and desire to secure by Letters Patent is:—

1. A safety-holder for neckties of the self-adjusting type and adapted to be looped around the neck, comprising in combination, a flat abutting plate provided at the top with a recess to engage with and allow the said plate to be pressed against the collar stud from below, and at least one pin rigidly mounted on and secured at substantially right angles to the flat abutting plate, the said pin being the means crosswise to penetrate the slip and the loop of the knot of the tie. 95

2. A safety-holder for neckties of the self-adjusting type, comprising in combination, an abutment in the form of an angle plate, the said angle plate having a groove at its upper end and an opening in its center portion, and at least one pin mounted at right angles and rigidly fixed to the lower member of the angle plate as a means to penetrate the slip and loop of the finished knot of the tie. 100

3. A safety-holder for neckties of the self-adjusting type, comprising in combination, an abutment in the form of an angle plate having a groove at its upper end, and three pins mounted at right angles and rigidly secured to the lower member of the angle plate, two of the said pins being symmetrically arranged in relation to each other and to the longitudinal center line of the angle plate and the third pin being mounted below the other pins and on the center line. 110

4. A safety-holder for neckties of the self-adjusting type, comprising in combination, an abutment in the form of an angle plate having a groove at its upper end, and three 115

undulated pins mounted at right angles to the lower member of the said angle plate, two of the said pins being symmetrically arranged in relation to each other and to the 5 longitudinal center line of the plate and the third pin being mounted below the other pins and on the said center line.

In testimony whereof I have hereunto set my hand in the presence of two subscribing witnesses.

JOSEF PABST.
